MULTIPLE POLE FUSED DISCONNECT SWITCH

August R. Schrade, 2814 Reuter Ave.,
Waco, Tex. 76708
Filed Sept. 24, 1965, Ser. No. 489,939
4 Claims. (Cl. 200—114)

This invention relates to electric switches and more particularly to that type of switch known as a multiple pole switch.

So far as is known, there never has been commercially available a two pole, three wire switch that one could fuse with utility company type of fuse links, and when one of the fuse links were blown, it would cause the switch (or secondary breaker) to open all of the poles of the switch.

It is therefore the principal object of this invention to provide a multiple pole electric switch that will meet the above noted conditions.

Another object of this invention is to provide a multiple pole electric switch of the character described that is designed for use near the top of an electric light pole.

Another object of this invention is to provide a multiple pole electric switch that is provided with a handle for the manual opening or closing of the switch.

Another object of this invention is to provide a multiple pole electric switch having an indicator on the outside thereof that will indicate whether the switch is open or closed.

Still another object of this invention is to provide a multiple pole electric switch having a minimum number of simply constructed parts all enclosed within a single rectangular box.

Other and further objects of this invention will come to mind as the description of the invention proceeds.

In the drawing:

FIGURE 1 is a perspective view of this invention with its rectangular box shown in phantom lines.

FIGURE 2 is a perspective view of this invention secured to the upper end of an electric transformer and connected to the power lines.

Directing one's attention to FIGURE 1 of the accompanying drawing, it will be seen that this invention consists of a plurality of levers, the first one of which is a horizontally disposed lever 5 that is swingably hinged at 6 and which has its outer end 7 swingably supporting the upper end of the vertically disposed lever 8 that has its lower end connected to flag supporting arm 9 in the same way that the vertical lever of bar assembly 38 is secured to arm 42. A horizontal shaft 10 extends across the switch box to which is secured one end of the trip arm 11 and handle 12. A second and longer horizontally disposed common tripping bar 13 is hinged at 14 and is provided with a U-shaped recess 15 in the upper edge thereof. A coil spring 16 has one end secured to the outer end of the aforesaid bar 13, while the other end of the spring is secured to the inside of the top of the rectangular switch box 17 which is shown in phantom lines in the aforesaid FIGURE 1 of the drawing. A vertically disposed latch arm 18, having a rectangular opening 19 in the outer end 20, projects upward from the rectangular flapper block 21 to which it, the aforesaid latch 18 is secured. A flexible wire 30' leads from the aforesaid flapper block 21 to the lower end of the fuse link 22 that has its upper end secured to a connection that is in turn connected to the wire 23 that leads to one of the two line wires of an electric power line. Still another horizontally disposed lever 24 that is even longer than lever 13 is hinged at 25. This last-mentioned lever has one end of the coil spring 26 secured thereto, while the other end of the same coil spring is secured to the

2

inside of the top of the aforesaid rectangular switch box 17. A second rectangular flapper block 27 is in normal parallel spaced relation to the first-mentioned flapper block 21 when this electric switch is open. The block 21

5 is secured to the L-shaped spring loaded arm 28. The first-mentioned flapper block 21 is provided with two electric switch contacts of which only one, namely, electric contact 29 is visible in FIGURE 1 of the drawing. Contact 29 is connected by the previously mentioned wire 30' to the aforesaid fuse link 22, while the second-mentioned contact is connected by the wire 30 to the lower end of the second vertically disposed fuse link 31 that is suitably connected to the wire 32 that leads to the second line wire of the electric power line. The laterally disposed bar 33 that is mounted under levers 5 and 24 has each end secured to the swingably mounted lugs 34 and 35, each one of which has its other end swingably secured by the stub shafts 36 and 37, the purpose of the laterally disposed bar being to trip the tripping bar 13.

20 The Z-shaped hinged bar assembly 38 which is made up of horizontally disposed lever 5, vertically disposed lever 8' and horizontally disposed flag supporting arm 42, also drops down and trips tripping bar 13 when fuse link 22 is blown. A rectangular flag 41 is secured to the lower horizontally disposed flag supporting arm 42 of the aforesaid hinged bar assembly 38, thereby giving one visual warning that the electric switch is open. An alike construction is employed to support the second rectangular flag 43 that is located on the other side of this 25 novel invention. A coil spring 44 biases this aforesaid flag assembly towards switch opening position which is also the position in which flag 41 is displayed. A spring-loaded L-shaped rod 45 having an external indicating member 46 secured to the L-shaped rod 45 is so arranged as to indicate the open and closed position of the flapper block 21 of this invention. The only other major part of this invention that has not been mentioned is the two (only one visible) electric contact 47 that projects through the aforesaid rectangular flapper block 27. The contact 47 and its alike contact which is not shown is so positioned in the flapper block 21 as to come in contact with contacts 29 that project through the flapper block 21. Electric wires 48 that are connected to the power line pass through the insulators 49 that are in the 30 top of the aforesaid rectangular switch box 17.

The way that this invention of mine works is as follows:

When the switch is open and no fuses blown the elements of the switch are in the position shown in FIGURE 50 1 with contacts 29, 47 and the identical set of contacts which are not shown, open. Indicating member 46 is in a position to indicate that the switch is open.

To close the switch, grasp handle 12 and rotate shaft 10 to bring trip arm 11 into contact with L-shaped spring 55 loaded arm 28 to move this arm and flapper block 21 into the position in which contacts 29 and 47 are closed. In this position U-shaped recess 15 in horizontal tripping bar 13 and opening 19 in vertically disposed latch arm 18 interlock, to hold the switch closed. In closing the 60 switch L-shaped spring loaded arm 28 rotates spring loaded L-shaped rod 45 and indicating member 46 to a position in which the indicating member 46 indicates that the switch is closed.

If it is desired to open the switch, shaft 10 is rotated 65 in the opposite direction, lever 50 and link 51 pull down on lever 24. Lever 24 lowers laterally disposed bar 33. Laterally disposed bar 33 lowers horizontally disposed tripping bar 13 which disengages latch elements 15 and 19 and permits spring 28' to move L-shaped spring loaded arm 28 and flapper block 21 to switch opening position. At the same time indicating member 46 moves to indicate that the switch is open.

Suppose that there is an overload on the circuit. Fuse 22 or 31 blows. Suppose it is fuse 22. Arm 42 pivots about its pivot 41 to lower flag 42 into visible position. At the same time vertically disposed lever 8' is lowered. Vertically disposed lever 8' pivots horizontally disposed arm 5' about pivot 39 to contact laterally disposed bar 33 and lower it. Lowering laterally disposed bar 33 pivots horizontally disposed tripping bar 13 about its pivot 14 and disengages latch elements 15 and 19. This permits spring 28' to pivot L-shaped spring loaded arm 28 and flapper block 21 to open both sets of contacts 29, 47 to completely disconnect the power. Indicating means 46 indicates that the switch is open, while flag 41 indicates that the switch was opened because fuse link 22 was blown.

At this time, fuse link 22 can be replaced and the parts will be in the position shown in FIGURE 1.

Likewise blowing of fuse link 31 will operate to open both sets of switch contacts 29 and 47.

While I have indicated a preferred embodiment of this invention, many modifications may be made without departing from the spirit of the invention, and I do not wish to be limited to the precise details set forth, but desire to avail myself of all changes within the scope of the appended claims.

Having described my invention, what I claim as new and desire to secure by Letters Patent of the United States is:

1. A fused multipole disconnecting switch, comprising a plurality of substantially parallel substantially horizontal flag supporting arms, one end of each flag supporting arm pivotally mounted on a support member, a flag secured to the other end of each flag supporting arm, a vertically disposed fuse link for each flag supporting arm, a connection between the lower end of each fuse link and the other end of said flag supporting arm, a conductor connected to the upper end of each fuse link and connected to a fixed support for supporting said upper end of said fuse link, a first rectangular flapper block located above said flag supporting arms and secured to a fixed support, a second rectangular flapper block pivotally secured to the first flapper block, a set of mating contacts for each flag supporting arm, a contact of each set secured to each flapper block, spring means biasing said second flapper away from said first flapper block, a latch secured to the second flapper block and to a fixed support for latching the pivoted flapper block in contact closing position, a separate wire connecting to each contact of said first flapper block for connection to line wires, a separate wire connecting each contact of the second flapper block to the lower end of each fuse, means connected to each flag supporting arm and to the latch operated on dropping of either flag due to the corre-

sponding fuse being blown for releasing the said latch, whereby on blowing of any fuse the corresponding end of a flag supporting arm and flag will drop down and will release the latch to permit the spring means to separate the contacts of each pair of mating contacts.

5 2. The combination of claim 1 including a switch box enclosing said switch mechanism, the flag supporting arms being near the bottom of the switch box and the box having an opening in the bottom thereof for each flag through which opening said flag projects when its fuse blows and the flag drops down.

10 3. The combination of claim 2 in which the first flapper block is in substantially vertical position, the pivot for the flapper blocks is along the lower edge of said first flapper block, the latch mechanism comprises a vertically disposed latch arm secured to said second flapper block and extending in substantially the same plane as said second flapper block, the latch arm has an opening therethrough, a horizontally disposed tripping bar extends through said opening in said latch arm, one end of said tripping bar pivotally mounted on a support member, spring means secured to said tripping bar and a fixed support for biasing said tripping bar upward and a U-shaped recess in the upper edge of said tripping bar to engage the upper part of the opening in the latch arm when the contacts of the flapper blocks are closed.

15 4. The combination of claim 3 in which the means for tripping the latch comprises a horizontally disposed bar eccentrically pivoted to fixed supports, said horizontally disposed bar extending transversely of said tripping bar closely above said tripping bar, a vertically disposed lever for each flag supporting arm, a connection between the lower end of each vertically disposed lever and an intermediate point of its flag supporting arm, a horizontally disposed lever for each flag supporting arm, each last mentioned horizontally disposed lever extending over said laterally disposed bar, each last mentioned horizontally disposed lever having one end secured to the upper end of one of said vertically disposed levers and the other end pivotally secured to a fixed support.
